ASH TRAY

Donald V. Burgess, Cut Bank, Mont.

Application May 23, 1950, Serial No. 10,104

Term of patent 14 years

(Cl. D85—2)

To all whom it may concern:

Be it known that I, Donald V. Burgess, a citizen of the United States, residing at Cut Bank, in the county of Glacier and State of Montana, have invented a new, original, and ornamental Design for an Ash Tray, of which the following is a specification, reference being had to the accompanying drawing, forming part thereof.

Figure 1 is a view in top plan of an ash tray, showing my new design;

Figure 2 is a view in side elevation; and

Figure 3 is a view in front elevation.

The bottom of the ash tray, not shown, is a plane surface.

I claim:

The ornamental design for an ash tray, substantially as shown and described.

DONALD V. BURGESS.
